ABRASIVE ARTICLE AND METHOD OF
MAKING THE SAMEGeorge H. Davis, Niagara Falls, N. Y., assignor
to The Carborundum Company, Niagara Falls,
N. Y., a corporation of Pennsylvania

Application October 17, 1931, Serial No. 569,447

6 Claims. (Cl. 51—278)

The present invention relates to flexible abrasive fabrics, and particularly to a method for increasing the flexibility of such material.

Heretofore, in the manufacture of flexible abrasive fabrics, it has been proposed to increase the flexibility by passing the material over flexing bars in two directions, at right angles, which process will break or crack the abrasive coating in lines which are mutually perpendicular and are diagonal to the fabric. Such method of flexing does not wholly flex every portion of the fabric but leaves spaces between the lines thus flexed. This renders a partial flexibility of the material which tends to reduce or impair its quality.

In accordance with the present invention, the abrasive material is flexed uniformly throughout its entirety or, if desired, only along the edges. By means of balls operating under pressure upon the back of the abrasive fabric, the breaks occur substantially in radial form about each particle of grain, leaving no one portion of the fabric untreated. The formation of breaks about the grain particles results in an increase in flexibility of the abrasive-coated fabric and in an article which is materially superior to abrasive-coated fabrics flexed by previously used methods.

Other advantages of my invention will become apparent from a perusal of the drawings forming part of this application, wherein:

Fig. 1 is a diagrammatic side view of the flexing apparatus with the abrasive fabric passing therethrough;

Fig. 2 is a plan view of the under-surface of the pressure plate;

Fig. 3 is a diagrammatic view of the flexing apparatus showing its application to the edges of discs;

Fig. 4 is a diagrammatic view of the flexing apparatus similar to that shown in Fig. 3, but using a conical type of roller;

Fig. 5 is a perspective view of an abrasive disc supported on a supporting disc showing radial slits and flexed edges;

Fig. 6 is a diagrammatic microscopic view of a piece of flexed fabric showing the form of breaks;

Fig. 7 illustrates a modification of the method illustrated by Fig. 1 in which cylindrical supporting surfaces are used to mount the abrasive-coated fabric and the compression balls respectively;

Fig. 8 is a section on the line VIII—VIII of Fig. 7;

Fig. 9 illustrates the character of the breaks

made by the apparatus of Fig. 7 when both rolls are driven at the same speed; and

Fig. 10 illustrates the character of the breaks made by the apparatus of Fig. 7 when the two rolls are driven at different rates of speed.

Referring to Fig. 1, a pressure plate 2, preferably of steel or similar material, is secured to a rigid plate 1 by means of adjustment screws 3. Within the pressure plate 2 are mounted, by means of a race 4, balls which may be of steel or similar material. These balls 5 are positioned and held in place in the same fashion as it is customary to mount ball bearings, and may be of any size, the size of the balls governing the number of breaks or cracks made in the fabric, and thus also governing the flexibility of the fabric produced. Should it be desired to procure a fabric with the highest possible degree of flexibility, small balls are used in the pressure plate since they create the largest area of cracks or breaks which will cross and re-cross one another, due to the fact that the areas of the breaks made by each ball intermingle with, or overlap, each other. This overlapping of areas with the consequential crossing of the breaks insures a very fine network of breaks and cracks, as shown in Fig. 6, which renders the fabric exceptionally flexible.

On the other hand, if a fabric is desired which has but a small degree of flexibility, large balls are used. It will be apparent that, due to their slight curvature, such large balls do not cause as sharp an angle of depression as the small balls and thus do not make as numerous breaks in the coating of the fabric; furthermore, due to this fact and to the fact that obviously a smaller number of large balls may be mounted in the pressure plate, the lines of greatest intensity of the breaks are not as close, nor do the areas of the breaks so made overlap to any appreciable extent in order to bring about the fine network of breaks produced by the small balls.

However, it is not to be understood that in using the large balls, areas are left which remain unflexed since, in the performance of my method, I mount the balls in the pressure plate in staggered relation in order that portions remaining unflexed after its passage beneath the first ball will be treated by the next succeeding ball. One such arrangement of these balls is shown in Fig. 2 but, of course, it is to be understood that the arrangement depends on the size of the balls used and the desired proximity of the breaks to each other, as well as on the width of the fabric to be flexed; moreover, the size of the ball to be used is

governed by the size of the grit of the abrasive fabric since a good grade of flexibility could not be obtained upon a coarse grit fabric by the operation of small balls thereon. In the latter case 5 the small balls would press above individual grain particles, thus preventing any ball pressure on the adhesive between them.

In performing my invention, the coated abrasive fabric is conducted to the flexing apparatus 10 where the uncoated surface is passed next to the pressure plate 2 and the entire abrasive strip travels between the balls 5 and a continuous rubber belt 6 which acts as a pad for the coated surface of the abrasive fabric. This belt 6 moves 15 around rolls 9 and 10 at a speed substantially equal to the speed at which the abrasive fabric is caused to travel. The synchronized movement of both the belt 6 and the abrasive fabric prevents any undue cutting or tearing of the rubber belt by the abrasive grains, which would otherwise be the case should the abrasive fabric travel at a faster rate than the belt, or the belt remain stationary during the forward movement 20 of the abrasive fabric.

25 As the abrasive-coated fabric passes between the ball 5 of row A and the rubber belt 6, the force or pressure of the flexing apparatus (exerted by means of the adjustment screws 3) causes the coated fabric to be strained under locally applied 30 pressure of the ball 5 and thus causes the adhesive coating to be cracked and broken in those areas where the ball 5 creates a strain upon the fabric. As the fabric, together with the rubber belt 6, passes on, by reason of each row being 35 slightly offset from the preceding row, those portions which are not flexed by the ball 5 in row A are treated by the balls 5 in the next rows B, C and D.

40 The yielding of the rubber belt 6 beneath the abrasive-coated fabric tends to allow the balls to offer a greater strain upon the fabric and thus permits a larger area of breaks than would be possible with a belt or pad having no elastic properties; however, to give the rubber belt some 45 resistance, a steel plate 8 is provided beneath the under-surface of the rubber belt 6.

Means, other than the pressure plate 2 and rubber belt 6, may be used as effectively and efficiently in this method of flexing abrasive fabric, 50 such as using a steel roll containing steel balls mounted in the staggered relation indicated as in Fig. 7, and a companion roll of rubber. The paper to be flexed is passed between the steel roll and the rubber roll, the abrasive side of the fabric coming in contact with the upper side of the rubber roll, and the balls mounted in the steel roll 55 acting upon the uncoated surface of the fabric, to flex it, substantially as described.

60 Using this means of flexing, the degree of flexibility, which is governed by the increase or decrease in breaks, may be controlled by the respective speeds of both rolls. Should both rolls travel at substantially the same speeds, distinct areas of breaks would occur (see Fig. 9) which 65 would tend to give a small number of breaks with little overlapping. On the other hand, if the roll acting as the rubber pad (upon which the fabric is supported) is driven at a faster or slower rate of speed than the pressure roll, there will be 70 an increase in the number of breaks inasmuch as the fabric will be able to receive the repeated pressure of the balls mounted in the pressure roll as illustrated in Fig. 10. In Fig. 9 the breaks are 75 of the character made by the balls when each ball presses the back of the abrasive sheet for a

very short time. In Fig. 10 the breaks are of the character made by the balls when they roll over the back of the abrasive sheet for an appreciable period of time. The use of small rollers in place of balls in the steel roll or pressure plate is still another means for accomplishing essentially the same result.

Using the principle of my improved process in substantially the same manner, the edges of abrasive coated discs may be flexed so as to give them 10 a greater degree of flexibility and better adaptation for the various uses to which they are put. The rubber pad or belt 6' is in this instance circular and is positioned upon a circular plate 8' which is supported by any suitable revolving 15 standard 12, as shown in Fig. 3. The pressure member 2' with the desired number of balls mounted thereon is attached to a stationary lever 13 which is held under pressure to exert the necessary force of the balls upon the uncoated side 20 of the abrasive paper. It is to be understood that a stationary standard and a revolving pressure member may be substituted, if desired.

The pressure member (using the apparatus of Fig. 3) may be so positioned with relation to the 25 edge of the disc that the flexing will occur either from a given concentric circle to the edge, or from a given concentric circle to a larger concentric circle but not to the edge. The latter flexing is most advantageous since it permits the 30 edges of the disc to be bent under without the usual danger of breaking, and yet does not detract from the necessary and desired stiffness of the edges. It will be apparent that discs flexed in this manner are particularly adapted to be attached to a supporting disc and, as such, are of 35 greater value than ordinary discs.

Furthermore, should it be desired to flex the disc so that the edges may be bent under and at the same time be flexible, it is proposed to first 40 flex the disc, through the use of apparatus mentioned immediately above (see Fig. 3), from a given concentric circle but not to the edge; then, in order to make the edges circumferentially flexible, a cone (see Fig. 4) is substituted for the 45 pressure member containing the balls. The cone remains in a stationary position while the abrasive disc is revolved, by means of the standard, beneath the cone in a circular path, and it gives to the fabric horizontal flexed lines (adjacent the 50 circumference and concentric therewith), which are superimposed upon the first mentioned lines.

In order that these flexed discs may be more easily bent over the edges of any supporting disc and may present, in addition, a neat appearance 55 when attached thereto, I have provided radial slits 14 about the edges of the discs, as shown in Fig. 5. These slits are spaced equidistantly at any predetermined distance, the distance depending upon the radius of the abrasive disc and the corresponding radius of the supporting disc, and are made in the discs by means of die stamping by cutting with knives or by any other process known in the art.

It will be appreciated that such slits, or similar 65 cut-out portions, along the edges of these discs will greatly enhance the commercial value of my product, since such slits complement and add to the flexibility of the edges produced according to this invention.

Various other additions and modifications may be made with relation to my herein-described 70 method but it is to be understood that they will be within the scope of my invention as described in the appended claims.

I claim:

1. As a new article of manufacture, an abrasive-coated disc having radial slits disposed equidistantly about the edge of the disc, having lines of breakage at random directions starting from a continuous series of points distributed along an annular portion of the coated abrasive which portion is concentric to the periphery of said disc, and having uniformly distributed lines of breakage superimposed upon said first mentioned breaks.
2. An abrasive disk of approximately circular form having a stiff central portion surrounded by an annular portion in which the binder is broken in short cracks extending from a series of points which lie equidistant from the center of the disk and adjacent its edge.
3. The abrasive disk described in claim 2 in which an annular portion adjacent the edge of the disk is also flexed along lines radial to the center of the disk.
4. The abrasive disk described in claim 2 in which an annular portion adjacent the edge of the disk is slit along radial lines.
5. An abrasive sheet of approximately circular form having a relatively stiff central portion and a more flexible annular portion adjacent to the outer circumference of the sheet, said annular portion of the abrasive article being flexible by virtue of the binder being broken in random directions.
6. An abrasive sheet of approximately circular form having a relatively stiff central portion and a more flexible annular portion adjacent to the outer circumference of the sheet, said annular portion of the abrasive article being flexible by virtue of the binder being broken in random directions and also in directions radial to the circular sheet.
